(57) **CLAIM**

The ornamental design for a container with an additional compartment, as shown and described.

DESCRIPTION

FIG. 1 is a perspective view of a container with an additional compartment, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view in which the additional compartment is shown attached to the container.

The broken lines depict portions of the container with an additional compartment that form no part of the claimed design.

1 Claim, 8 Drawing Sheets
